UNITED STATES PATENT OFFICE.

OTTO U. JAHELKA, OF BALTIMORE, MARYLAND.

TOBACCO-BAG MOUTH.

1,370,448.

Specification of Letters Patent.

Patented Mar. 1, 1921.

Application filed January 3, 1920. Serial No. 349,214.

To all whom it may concern:

Be it known that I, OTTO U. JAHELKA, a citizen of Switzerland, having on July 29, 1919, taken out his first papers to become a 5 citizen of the United States of America, (No. 9,134, District Court of U. S. for the District of Maryland,) residing at W. Hamilton, Baltimore, in the State of Maryland, have invented new and useful Improvements 10 in Tobacco-Bag Mouths, of which the following is a specification.

The object of the invention is to provide a dispensing mouth or outlet collar for bags and sacks such, for example, as those used 15 to contain tobacco and from which the contents are discharged, a little at a time in the filling of pipes, the forming of cigarettes and the like, the purpose being to construct a device of this kind which is adapted for 20 interchangeable application successively to the bags or sacks in which the tobacco or similar material is placed upon the market as a means of controlling the discharge with a minimum of waste and maximum of facility so far as the operator is concerned without resort to the alternate loosening and 25 tightening of the draw string or cord with which the mouths of receptacles of this type are ordinarily provided, and the manipulation 30 of which necessitates the use of both hands or the mouth and one hand, it being a common practice to grasp the tag which is usually attached to one loop of the draw string between the teeth while drawing upon 35 the other loop to close the bag mouth; and with these objects in view the invention consists in a combination and construction 40 of parts of which a preferred embodiment is shown in the accompanying drawing, wherein:

Figure 1 is a side view of the dispensing mouth or collar applied in the operative position to a bag or sack, a portion of the latter being broken away.

Fig. 2 is a plan view of the same.

Fig. 3 is a longitudinal sectional view of the mouth or collar taken on the plane indicated by the dotted line 3—3 of Fig. 2.

Fig. 4 is a transverse section on the plane 50 indicated by the line 4—4 of Fig. 2.

The device consists essentially of a preferably elongated cap adapted to be pressed or otherwise formed from a sheet metal blank to produce a top plate 10 and a depending flange 11 contracted to produce a 55 reduced neck 12 having an exterior groove

13 below which the flange is enlarged or bulged as shown at 14. The upper wall of the groove 13 extends outward to form a shoulder 15 which is substantially parallel 60 with the under surface of the top plate 10 to define therewith an intervening groove or guide 16 in which is mounted the edges of a sliding cover 17 preferably having a knob or finger hold 18, said slide or cover 65 serving as a closure for an outlet slot 19 formed preferably longitudinally with reference to and near one end of the cap plate 10.

The elongated, substantially elliptical plan 70 of the cap serves to adapt it to perform the functions of a grip by which the attached bag or sack shown at 20 may be handled, and obviously a finger of the hand grasping the same may readily be employed by engagement with the knob or finger hold 18 to withdraw the slide to a greater or less extent and hold it in such withdrawn position while the required portion of the contents of the bag or sack is being discharged 80 to fill a pipe or charge a cigarette paper, and when a sufficient quantity has been discharged a reverse movement of the same finger of the hand grasping the cap will return the slide to its closed position where its 85 free edge will engage under or pass into underlapping relation with the lip 21 formed by the portion of the cap plate at the adjacent end of the discharge opening or slot 19. 90

It will be understood moreover that more or less frictional engagement of the walls bounding or defining the guide groove 16 with the outer and inner surfaces of the slide may be produced to insure the substantial retention of the slide in adjusted positions, either closed or open, and such frictional engagement may be increased from time to time as may be preferred by the operator or may be required to compensate for 95 wear, by merely pinching toward each other the opposed walls of said guide represented respectively by the upper side of the neck 12 and the cap plate. 100

It will be seen that the slide is located 105 near one end of the grip formed by the cap and when moved to permit the discharge of the contents of the bag is not interferred with in any way by the hand grasping the same. The attachment of the bag or sack 110 to the cap is effected by the tightening and fastening of the draw string or cord 22 of

the bag in the groove formed by the reduced neck portion of the device so that said cord and the sheath in which it is fitted are housed within the groove and do not interfere with the proper grasp of the device by the hand of the operator.

5 What is claimed is:

An interchangeable dispensing mouth or cap for bags having a collar provided with
10 a top plate and an intermediate reduced or neck portion forming an exterior circum-

ferential groove of which the upper side is spaced from the plane of said top plate to define an interposed guide groove, said plate being provided at one end with an outlet 15 opening, and a sliding closure fitted at its edges in said guide groove and frictionally engaged by the opposed walls defining the same.

In testimony whereof I affix my signature.

OTTO U. JAHELKA.
